UNITED STATES PATENT OFFICE.

SAMUEL C. TATUM, JR., OF CINCINNATI, OHIO, ASSIGNOR TO SAMUEL C. TATUM & CO., OF SAME PLACE.

SEWING-MACHINE TREADLE.

SPECIFICATION forming part of Letters Patent No. 276,502, dated April 24, 1883.

Application filed December 19, 1882. (No model.)

To all whom it may concern:

Be it known that I, SAMUEL C. TATUM, Jr., of Cincinnati, Hamilton county, Ohio, have invented a new and useful Improvement in 5 Sewing-Machine Treadles, of which the following is a specification.

In sewing-machine treadles heretofore in use vibrating by knife-edges upon the supporting-bar or brace-rod, such rod has been 10 grooved at remote parts of its length to receive projections from the treadle. A serious objection has arisen to this method, owing to the liability of such grooves to be formed out of alignment, thus causing the projections to bind and jam within the grooves and cause the 15 treadle to labor and to unnecessarily fatigue the operator.

My improvements have in view the doing away with the above laborious and unsatisfactory method.

In the accompanying drawings, Figure 1 is a perspective view of a sewing-machine treadle and accessory parts embodying my invention. Fig. 2 is a partly sectional elevation of the 25 same. Fig. 3 represents a part of the bearing-rod with inverted-V bearing and confining lip or yoke and portion of corresponding treadle. Fig. 4 shows a modification in which the bearings are located within the treadle.

30 A may represent the lower part of a sewing-machine frame; B, a rod which serves both to brace the frame and to support shells C, having inverted-V-formed ridges c, which constitute the fulcrums upon which rest the 35 slightly more obtusely notched or inverted-V-recessed lugs that project from the treadle D. The shell C has an obliquely-presented lip, c', that, projecting over the correspondingly oblique ridge of the lug d and bearing closely 40 upon it, serves to prevent any accidental rising of the treadle off of its proper bearings, and at the same time prevents any lateral displacement. The shells C, having been adjusted to their proper place upon the bearing-rod B, 45 both longitudinally and circumferentially of

said rod, so as to cause their inverted-V ridges to occupy the corresponding notches of the treadle-lug without binding therein, are firmly secured thereto by means of screws E.

Instead of extending laterally outward from 50 the treadle, as in Figs. 1, 2, and 3, the lugs may project within the treadle and be held by reversely-presented shells, as shown at Fig. 4.

It is apparent that the capacity of circumferential adjustment of the shell C completely 55 overcomes the liability of the non-adjustable edges of the ordinary treadle to bind within the notches of the bearing-rod arising from the lack of absolute alignment of those parts, such as frequently occurs.

Sewing-machine treadles bearing upon knife-edge supports and having straight covers or confining-lips have been made; but such bearings do not admit of adjustment as to wear and for keeping the treadle close to its bearings, so as to prevent rattling and lost motion; and such treadles have also been made with knife-edges in treadle-bearings in grooves cut in the bearing-rod itself; but such bearings admit of no adjustment circumferentially of 65 the rod when the grooves in the rod are not cut exactly in alignment, which is generally the case. I therefore do not claim such bearings or such confining-lips, separately considered.

70 I claim as new and of my invention—
75 In combination with a treadle-rod and treadle having grooved lugs of a sewing-machine, the longitudinally and circumferentially adjustable shells C, having knife-edge projections c, occupying the grooved treadle-lugs, and oblique lips c', overhanging and bearing on the upper sides of said lugs, in the manner and for the purpose set forth.

80 In testimony of which invention I hereunto 85 set my hand.

SAM. C. TATUM, JR.
